[57] CLAIM

The ornamental design for a belt-attached can holder, as
shown and described.

DESCRIPTION

FIG. 1 is a top perspective view of a belt-attached can
holder showing my new design;

FIG. 2 is a bottom perspective view thereof;

FIG. 3 is a side elevational view thereof, the broken line
showing of a bucket and brush is for illustrative pur-
poses only; and

FIG. 4 is a front elevational view in extending position.

FIG. 1

FIG. 2

FIG. 3

FIG. 4
